UNITED STATES PATENT OFFICE.

WILLIAM EDWARD HOLMES MORSE AND OLIVER HAMMOND BEMIS, OF ALGONA, IOWA.

COMBINATION-LOCK.

SPECIFICATION forming part of Letters Patent No. 662,285, dated November 20, 1900.

Application filed June 27, 1900. Serial No. 21,738. (No model.)

To all whom it may concern:

Be it known that we, WILLIAM EDWARD HOLMES MORSE and OLIVER HAMMOND BEMIS, citizens of the United States, and residents of Algona, in the county of Kossuth and State of Iowa, have invented a new and Improved Combination Door Lock and Knob, of which the following is a full, clear, and exact description.

10 The object of the invention is to provide a new and improved combination door lock and knob arranged to work the door-lock by the use of the outside knob, which latter is adapted to be set to any desired combination to prevent unauthorized persons from opening the door and to allow the owner to readily unlock and open the door without the use of a key.

15 The invention consists of novel features and parts and combinations of the same, as 20 will be fully described hereinafter and then pointed out in the claims.

25 A practical embodiment of the invention is represented in the accompanying drawings, forming a part of this specification, in which similar characters of reference indicate corresponding parts in all the views.

Figure 1 is a cross-section of the improvement as applied. Fig. 2 is a sectional front elevation of the same on the line 2 2 in Fig. 30 1, and Fig. 3 is an enlarged sectional plan view of the outside knob, the section being on the line 3 3 in Fig. 5. Fig. 4 is an enlarged cross-section of the same on the line 4 4 in Fig. 5. Fig. 5 is an enlarged face view of the 35 outside knob with the cover therefor removed, and Fig. 6 is a sectional plan view of the same on the line 6 6 in Fig. 5.

In the door A is arranged the usual door-lock B, of any approved construction and 40 adapted to be operated by the inner section C of a divided spindle, the outer section C' of which is adapted to be locked to the inner section, so that the spindle can be turned from either the outside or the inside to unlock the door. The inner spindle-section C is provided with a knob D, and the outer spindle-section is mounted to turn and to slide transversely in a hub E, projecting from a 45 escutcheon E², secured to the outside of the door in the usual manner. On the outer spin-

dle-section C' is secured or formed a knob F, containing a combination mechanism which normally prevents the knob F and the spindle-section C' from being moved inward to engage the spindle-section C' with the spindle-section C, so that unauthorized persons cannot open the lock upon turning the knob F; but a person knowing the combination mechanism can bring the knob into such position that 55 it can be pushed transversely to engage the inner end of the outer spindle-section C' with the spindle-section C to turn the latter, and thereby unlock the lock and open the door. For the purpose mentioned the adjacent ends 60 of the spindle-sections C C' are provided with groove and tongue C² C³, respectively, normally out of engagement, but moved into engagement when the spindle-section C' is moved transversely in an inward direction, 65 as above explained.

The grooved end of the spindle-section C is provided with a pin C⁴, adapted to abut against the face of the door and prevent the spindle-section C from being drawn out of 70 position in the door-lock, and a similar pin C⁵ is on the inner end of the spindle-section C' to limit the outward sliding movement of said spindle-section by the pin abutting against the inner face of the casing E'. The 75 pin C⁵ is pressed on opposite sides by the free ends of a spring C⁶, secured in the casing E' (see Fig. 2) to hold the spindle-section C' and the knob F in a normal position, as shown in Figs. 1, 2, and 5, the spring, however, allowing a transverse sliding of the pin C⁵ and the spindle-section C', for the purpose previously 80 mentioned.

On the outer end of the hub E is formed an annular flange E³, extending part way into an 85 annular groove F', formed on the back of the knob F, and the said annular flange E³ normally abuts against the rear faces of a plurality of slides G, mounted to move in radial grooves or guideways F², formed on the face 90 of the knob F. (See Figs. 5 and 6.) Each of the slides G is formed on its rear face with a groove G', adapted to register with the flange E³ when the slide is moved into proper position, as shown at the left in Fig. 6. 100 When all the slides G are in this position, then the knob F, with the spindle-section C',

can be moved inward to bring the tongue C^3 in engagement with the groove C^2 to connect the spindle-sections with each other and allow the operator on turning the knob F to unlock the lock B and permit of opening the door. As stated, the slides G, are with their grooves or notches G' , normally out of register with the flange E^3 , so that the knob F cannot be moved in an inward direction until the slides are moved by the operator to bring their notches G' in register with the flange E^3 , and in order to accomplish this result the following device is provided: Each slide G is pressed into an innermost position by a spring G^2 , but the inward movement of each slide is limited by a pin H, adapted to be set by the operator in one of a series of apertures H', extending in a radial line from the center of the knob, as indicated in Figs. 5 and 6. On the top of each slide are formed parallel ratchet-teeth racks $G^3 G^4$, of which the rack G^3 is adapted to be engaged by a spring-pawl I, secured on an arm I', fulcrumed at I² on the face of the knob F, as is plainly illustrated in Fig. 5. Each arm I' is pressed on at its free end by a spring I³, and said arm is also engaged by a pin J', secured to a button J, mounted to slide in a radial guideway F³, formed in the knob F, it being understood that the pin J' engages the arm I' on one side and the free end of the spring I³ engages the arm on the opposite side. Thus the pawl I, with its arm I' and the button J, are normally held under the tension of the spring I³ in the position shown in Fig. 5. When the operator presses the button J in an inward direction, then the pin J' imparts a swinging motion to the arm I' and the pawl I, so that the latter imparts an outward sliding movement to the rack G^3 and the slide on which the rack is secured, the slide moving outward against the tension of its spring G^2 . When the operator releases the pressure on the button J, the spring I³ returns the pawl I, arm I', and button J to their former positions, it being understood that the arrangement is such that at one inward pressure of the button J the pawl I moves the slide forward a distance corresponding to the length of a tooth on the rack G^3 . The other rack G^4 is engaged by a spring-dog K, secured to the face of the knob F, so that when the operator has pressed a button J inward and moved a slide outward a distance corresponding to the length of a tooth on the rack G^3 then the dog K engages a tooth on its rack G^4 and holds the slide against return movement when the pressure on the button J is released. Now when the operator presses the button J a second time the above-described operation is repeated—that is, the slide G is again moved outward and locked in the outermost position against return movement by the dog K.

Now when the several slides G are in their normal positions the grooves G' are out of register with the flange E^3 , and the spindle-section C' is held in the outermost position

shown in Figs. 1 and 6 by the flange E^3 abutting against the rear faces of the slides, and consequently the spindle-sections are out of engagement. In order to move the slides the desired distance to bring the grooves into register with the flange E^3 , the operator successively presses and releases the buttons J the desired number of times to bring the slides G into such outermost positions that their grooves G' register with the flange E^3 . It is understood that by the use of the pins H each slide can be set in such a position that the notch or groove G' of the slide is a different distance away from the flange E^3 than the other slides, and consequently the buttons J have to be pressed and released a different number of times, so as to bring the several slides into the proper position. When this has been done, the operator can move the knob F inward to engage the spindle-section C' with the spindle-section C and turn the latter upon turning the knob F to unlock the lock B and permit of opening the door.

In order to reseat the several slides G, the following device is provided: under the spring-pawl I and the spring-dog K extend the outer ends of levers L L', fulcrumed on the knob F and adapted to be engaged at their inner forward ends by an annular flange N' on a button N, mounted to slide on a post F⁵, forming part of the knob F. When the button N is pressed in an inward direction, a swinging motion is given to the several sets of levers L L', so that their forward ends lift the pawls I and the dogs K out of engagement with the racks $G^3 G^4$, so that the latter are immediately pulled inward against their pins H by the action of the springs G². The knob F is provided with a suitable cover or hood F⁶, through which extend the buttons J and N, the cover serving to protect the working parts in the knob from dust, moisture, &c.

Having thus fully described our invention, we claim as new and desire to secure by Letters Patent—

1. A door-lock having a divided spindle, the inner section of which engages the door-lock mechanism, and the outer section is mounted to slide transversely and is adapted to be moved in engagement with the inner section, to work the door-lock mechanism for opening the door from the outside, and a spring for yieldingly holding the outer spindle-section in proper axial position and allowing a limited turning or axial movement thereof, as set forth.

2. A door-lock having a divided spindle, the inner section of which engages the door-lock mechanism, and the outer section is mounted to slide transversely and is adapted to be moved in engagement with the inner section, to work the door-lock mechanism for opening the door from the outside, an escutcheon having a hub for the outer spindle-section to turn and to slide in, a knob secured on the outer spindle-section, and manually

controlled means on said outer knob and abutting against the escutcheon-hub, for normally holding the knob and outer spindle-section against inward movement, said means being movable to allow inward movement of the outer knob and its spindle-section, as set forth.

3. A door-lock, comprising a lock mechanism, a spindle made in sections, of which the inner section engages the door-lock mechanism and the outer section is mounted to slide transversely, and is adapted to be moved in engagement with the inner section to work the door-lock mechanism for opening the door, an escutcheon having a hub for the outer spindle-section to turn and to slide in, a knob on the outer spindle-section, and manually-controlled means on said outer knob, and comprising a mobile member normally engaging said escutcheon-hub and holding the knob and outer spindle-section against inward movement, said member being movable to register with the escutcheon-hub, to allow inward movement of the outer knob and its spindle-section, as set forth.

4. A door-lock, comprising a lock mechanism, a spindle made in sections, of which the inner section engages the door-lock mechanism and the outer section is mounted to slide transversely, and is adapted to be moved in engagement with the inner section to work the door-lock mechanism for opening the door, an escutcheon having a hub for the outer spindle-section to turn and to slide in, a knob on the outer spindle-section, and manually-controlled means on said outer knob, for engaging said escutcheon-hub and hold the knob and outer spindle-section against inward movement, said means being adapted to be moved in register with said escutcheon-hub, to allow inward movement of the outer knob and its spindle-section, the said means comprising spring-pressed slides movable on the knob and having grooves adapted to register with the escutcheon-hub, to allow an inward movement of the knob, buttons slideable on the knob and adapted to be pressed by the operator, and intermediate mechanism between the buttons and the slides, to move the latter when the buttons are pressed, as set forth.

5. A door-lock, comprising a lock mechanism, a spindle made in sections, of which the inner section engages the door-lock mechanism and the outer section is mounted to slide transversely, and is adapted to be moved in engagement with the inner section to work the door-lock mechanism for opening the door, an escutcheon having a hub for the outer spindle-section to turn and to slide in, a knob on the outer spindle-section, manually-controlled means on said outer knob, for engaging said escutcheon-hub and holding the knob and outer spindle-section against inward movement, said means being adapted to be moved in register with said escutcheon-hub, to allow inward movement of the outer knob and its

spindle-section, the said means comprising spring-pressed slides movable on the knob and having grooves adapted to register with the escutcheon-hub, to allow an inward movement of the knob, buttons slideable on the knob and adapted to be pressed by the operator, intermediate mechanism between the buttons and the slides, to move the latter when the buttons are pressed, and a releasing device for the said intermediate mechanism, to release the spring-pressed slides for resetting the same, as set forth.

6. A door-lock having a spindle made in sections, one of which engages the door-lock mechanism and the other is adapted to be moved in engagement with the first section, an escutcheon-hub in which the slideable spindle-section is mounted to turn and to slide, a knob on the said slideable spindle-section, spring-pressed slides mounted to slide in guideways on said knob and having grooves adapted to register with said hub, each slide having a pair of parallel ratchet-teeth racks, a spring-pressed pawl for engaging one of the racks of a slide, a button under the control of the operator, for imparting a swinging movement to said pawl, and a spring-dog for engaging the other rack of a slide, as set forth.

7. A door-lock having a spindle made in sections, one of which engages the door-lock mechanism and the other is adapted to be moved in engagement with the first section, an escutcheon-hub in which the slideable spindle-section is mounted to turn and to slide, a knob on the said slideable spindle-section, spring-pressed slides mounted to slide in guideways on said knob and having grooves adapted to register with said hub, each slide having a pair of parallel ratchet-teeth racks, a spring-pressed pawl for engaging one of the racks of a slide, a button under the control of the operator, for imparting a swinging movement to said pawl, a spring-dog for engaging the other rack of a slide, levers extending under said pawl and dog, and a button under the control of the operator and adapted to be moved in engagement with levers to impart a swinging motion thereto and release said pawls and dogs from said racks, to allow the slides to return by action of their springs, as set forth.

8. A combination-knob, comprising a hub, of which the spindle of the knob is mounted to turn and to slide, the hub having an annular flange, a knob proper having an annular groove for engagement by said flange, spring-pressed slides mounted to slide in guideways on said knob, and having grooves or notches adapted to move in register with said flange, adjustable means for limiting the inward movement of said slides, and a button-actuated mechanism carried by the knob and connected with said slides to move the same outward, as set forth.

9. A combination-knob, comprising a hub, of which the spindle of the knob is mounted to turn and to slide, the hub having an an-

nular flange, a knob proper having an annular groove for engagement by said flange, spring-pressed slides mounted to slide in guideways on said knob, and having grooves or notches adapted to move in register with said flange, adjustable means for limiting the inward movement of said slides, a button-actuated mechanism carried by the knob and connected with said slides to move the same outward, the said mechanism comprising buttons slideable in the knob, spring-pressed pawls adapted to be actuated by the buttons, and racks on said slides, and adapted to be engaged by said pawls to move the slides outward, as set forth.

10. A combination-knob, comprising a hub, of which the spindle of the knob is mounted to turn and to slide, the hub having an annular flange, a knob proper having an annular groove for engagement by said flange, spring-pressed slides mounted to slide in guideways on said knob, and having grooves or notches adapted to move in register with said flange, adjustable means for limiting the inward movement of said slides, a button-actuated mechanism carried by the knob and connected with said slides to move the same outward, the said mechanism comprising but-

tons slideable in the knob, spring-pressed pawls adapted to be actuated by the buttons, racks on said slides, and adapted to be engaged by said pawls to move the slides outward, and dogs carried by the knob and adapted to engage a second set of racks on said slides, to hold the slides against return movement, as set forth. 35

11. A permutation mechanism for locks and the like, comprising a casing formed with an opening therein, a member having a flange fitting in said opening, a slide mounted in the casing and having a notch, the notch registering with the flange to permit the relative movement of the casing and flanged member, means serving normally to hold the slide with the notch out of register with the flange, and manually-operated devices for moving the slide against said means. 40 45
